UNITED STATES PATENT OFFICE.

RICHARD M. CRAIG, OF SAN ANTONIO, TEXAS.

DISPLAY APPARATUS.

Application filed December 29, 1925. Serial No. 78,243.

This invention relates to a novel method of and means for alternately displaying an invested object and the effect of divestiture thereof, the invention being based on the principles of color absorption and the method embodying the invention being applicable to the display of merchandise for advertising purposes, the display of apparent transformation of objects for amusement purposes, and various other kinds of displays.

It is one of the objects of the invention, in one of the embodiments thereof, to provide for the display of the contents of cans, cartons, boxes, and containers in general, the container with the label thereon designating the character of the contents being displayed in one step of the carrying out of the method and the said container, in another step of the method, being caused to apparently disappear thus revealing to view the contents thereof, so that in this respect the invention constitutes a valuable advertising medium for such merchandise as is ordinarily packed in opaque containers and concealed from view until the container has been opened.

Another object of the invention is to provide for the interesting and attractive display of wearing apparel so that, in accordance with the principles of the invention, a dummy may, at one moment, be made to appear for example in street attire and, at another moment be made to appear attired in such undergarments as the merchant, employing the invention may desire to advertise, so that both outer and under garments may be displayed upon a single dummy and in a very mystifying manner that will be certain to attract and hold the attention of observers of the display.

In another embodiment of the invention, the object in view is to provide for the application of the method to an animate object, thus enabling the invention to be practiced on the stage to produce startling transformation effects.

In the accompanying drawings:

Figure 1 is a view partly in elevation and partly in section illustrating a container and its contents to be displayed in accordance with the present invention, the view also illustrating diagrammatically the lighting circuit by which the container is displayed;

Figure 2 is a view similar to Figure 1 illustrating another type of container and another kind of article of merchandise, together with

a diagrammatic illustration of the lighting circuit;

Figure 3 is a perspective view, partly broken away, illustrating the manner in which the displayed object may be made to apparently change in size, the view illustrating also the lighting circuit through the medium of which the object is displayed;

Figure 4 is a view in elevation with a part broken away, illustrating substantially the arrangement shown in Figure 1 of the drawings except that the light sources are located within the container to illuminate the same from within rather than from the exterior thereof;

Figure 5 is a perspective view illustrating a dummy, clothed in wearing apparel, in accordance with the principles of the invention, the view illustrating the appearance of the dummy when displayed under light rays of one spectral color;

Figure 6 is a similar view illustrating the appearance of the dummy when displayed under light rays of another color;

Figure 7 is a view illustrating the application of the principles of the invention to a theatrical transformation display, and the appearance of the display under light rays of one spectral color;

Figure 8 is a similar view illustrating the appearance of the display under light rays of another spectral color.

In the embodiment of the invention shown in Figure 1 of the drawings, the numeral 1 indicates in general a container resembling a can, and this container is of celluloid or some other transparent material and is of a distinctive color such for example as red. The numeral 2 indicates words or other matter constituting the equivalent of a label such as would appear upon such a container, and these words or other matter are represented in a pigment of a distinctive color such for example as green. Merchandise is disposed within the container and in the example illustrated in Figure 1 the numeral 3 indicates either natural or artificial olives which are promiscuously arranged within the container in the same manner that the actual product would be contained within an ordinary can. It will be understood of course that various fruits may constitute the contents of the container, depending of course upon the commodity to be displayed or advertised, and in accordance with the principles of the invention the packaged commodity

is to be displayed under light rays of contrasting colors to produce certain mystifying and interesting effects which will presently be more fully explained. As previously 5 stated, the invention involves a method of alternately displaying an invested object and the effect of divestiture thereof, and therefore, in the specific embodiment shown in Figure 1, the invested object constitutes the 10 natural or artificial olives 3 which are green in color as shown in the said figure, and the investing medium constitutes the container 1, and likewise, in accordance with the principles of the invention, the investing medium 15 or investment, and the invested object are of contrasting pigment colors. The effect of divestiture of the invested object is obtained by successively displaying the container and its contents under light rays of contrasting 20 spectral colors and the means whereby this may be accomplished is illustrated diagrammatically in Figure 1 of the drawings. The numeral 4 indicates any desired number of red light bulbs and the numeral 5 any desired 25 number of blue light bulbs which bulbs are so arranged with respect to the container and its contents as to provide for flooding of the same with red light rays when the red light bulbs are lighted and with blue light 30 rays when the blue light bulbs are lighted. The numeral 6 indicates a source of supply and the numeral 7 indicates in general any suitable type of automatic flasher. A conductor wire 8 is led from one side of the 35 source of current supply 6 and connected to one terminal of the sockets for all of the red and blue bulbs. The flasher 7 may be of any simple type and for example comprises a disk 9 of insulating material upon the face of 40 which are arranged two series of contacts, the contacts of one series being indicated by the numeral 10 and those of the other series by the numeral 11 and the contacts of the two series being arranged in staggered relation 45 and concentric to a shaft 12 by which the disk 9 is supported for rotation. A conductor wire 13 is led from the other source of the current supply and electrically connected with the shaft 12, and brushes 14 and 15 are 50 mounted in juxtaposition to the flasher disk and are arranged to respectively coat with the contacts 10 and 11 in the rotation of the disks. A conductor wire 16 is led from the brush 14 and connected to the other terminal 55 of the socket for each of the blue light bulbs 5, and a conductor wire 17 is led from the brush 15 and is connected with the other terminal of the socket for each of the red light bulbs 4. It will now be evident that as 60 the flasher is operated, the circuit will be closed first through the blue light bulbs thus flooding the container and its contents with blue light rays. Under these spectral rays the container will appear substantially black 65 and the contents 3 thereof will be invisible.

At the same time the matter 2 will appear a brilliant white as the pigment color in which the matter is represented corresponds substantially to the spectral color of the light rays under which the container and its contents are at this time displayed. In the continued rotation of the flasher disk and as one of the strips 11 comes into contact with the brush 15, the circuit will be closed through the red light bulbs 4, and the container and its contents will be flooded with red light 70 days. At this time the container 1 will be nearly invisible, due to the fact that the pigment color in which it is represented is the same as the color of the light rays under which the container and its contents are at this time displayed. Therefore the contents 75 3 will be displayed substantially black and the effect will be that of the container being suddenly removed, leaving the contents thereof exposed to full view of the observer. As the matter 2 is represented in a pigment color contrasting with the color of the red light bulbs 4, this matter will at such time appear 80 substantially black. It will be evident, at this point, that the invention consists in representing the object in one pigment color, investing the object with a transparent medium of a distinctive pigment color contrasting 85 with the color in which the object is represented, and displaying the invested object, during successive periods, under light rays of contrasting spectral colors so that under one period of display the container will appear 90 substantially opaque and the contents will be invisible, and, under another period of display the container will apparently be obliterated and the contents made to appear. It will be evident therefore that the invention 95 is not concerned to any considerable extent 100 with the character of the invested object or with the character of the investing medium and this fact will be further exemplified in the description of the other illustrated embodiments of the invention which is to follow. 105

In the specific description of Figure 1 reference is made to the employment of contrasting or complementary pigment colors as well as contrasting or complementary spectral colors, but the particular colors referred to need not necessarily be employed as any contrasting colors may be selected, the selection being controlled to a certain extent by the character of the commodity or merchandise to be displayed and also the conditions under which the invention is practiced. Likewise, in the specific embodiment illustrated in said Figure 1 it will be preferable to so arrange the light bulbs that the subject-matter of the display will be flooded with colored light 115 rays from all sides, although, under some conditions it may be found desirable to locate the sources of colored light rays in a manner to otherwise flood the subject-matter 120 of the display with light rays. It will fur- 125 130 135

ther be understood that the sources of colored light rays may be so arranged as to be completely hidden from view and, if the container and contents are disposed against or

5 in juxtaposition to a background of a dark neutral color, the medium through which the transformation effect is obtained will not be apparent to the observer.

Figure 2 of the drawings illustrates a 10 slight modification of the arrangement shown in Figure 1 and in this figure the numeral 18 indicates the container in the general form of a box resembling the ordinary candy box, except that it is of some light ray transmitting material such for example as celluloid and is of a distinctive pigment color as for example red. Any suitable matter such for example as words, may be represented, as indicated by the numeral 19, upon the lid 15 of the box, in a pigment of a distinctive color such for example as green which color is in contrast with the color of the material constituting the box. Ordinary bonbons, or 20 artificial representations thereof, indicated at 25 20, are arranged within the box in the general manner in which bonbons are arranged in an ordinary candy box, and in this instance the bonbons or representations thereof, which constitute the invested objects, are for example in brown or some other neutral color.

Suitably arranged in juxtaposition to the box and its contents are red light bulbs 21 and blue light bulbs 22, and a conductor wire 23 leads from one side of a source of current 30 supply 24 and is connected to one terminal of the sockets for all of the bulbs. A conductor wire 25 is led from the other side of the source of current supply to the shaft 26 of an automatic flasher 27 which may be 35 of the same general type as that shown in Figure 1 and may comprise a disk 28 of insulating material having a series of contacts 29 and 30 mounted upon its face and electrically connected with the shaft 26. Brushes 40 31 and 32 are arranged in juxtaposition to the flasher disk and in such manner as to coat respectively with the contact strips 29 and 30. A conductor wire 33 leads from the brush 31 and is connected to the other terminals 45 of the sockets for the sockets for the blue lights, and a conductor wire 34 is led from the brush 32 and connected with the other terminals 50 of the sockets for the red light bulbs.

55 It will be evident that, in the operation of the flasher, and as one of the contact strips 29 rides in engagement with the brush 31, the circuit will be closed through the blue light bulbs 22 thus flooding the box with blue 60 light rays with the result that the investing box or investing medium will appear substantially black and the matter 19 upon the lid thereof will appear a brilliant white, the contents 20 of the box being invisible. 65 In the continued rotation of the flasher disk

and as one of the contact strips 30 rides in engagement with the brush 32, the circuit will be closed through the red light bulbs 21 and at this moment the box will be substantially obliterated and the matter 19 represented 70 upon the lid thereof will appear substantially black, the contents 20 of the box appearing a deep and rich brown under the red light rays. It will now be apparent that while, in the embodiment of the invention 75 illustrated in Figure 1, the investing medium and the objects invested are represented in contrasting pigment colors, in the embodiment shown in Figure 2 the investing medium is of a distinctive pigment color whereas 80 the invested object is of a neutral color, and by a neutral color I mean a color which possesses no color characteristics such as are peculiar to primary colors, and which does not materially change under a distinctive 85 spectral color illumination.

Figure 3 of the drawings illustrates an embodiment of the invention wherein a representation of a large container and a representation of a smaller container within the 90 larger one may be successively displayed to the view of observers either for advertising or for amusement purposes, and in this figure the numeral 35 indicates a representation of a container such for example as a can which is 95 of light ray transmitting material such for example as celluloid and of a distinctive color such for example as red. Suspended or supported in any desired manner within the container representation 35 is a representation 100 36 of a smaller container having however the same shape and proportions as the large container 35. This container 36 will likewise be of a distinctive color as for example green. Blue light bulbs 37 and red light 105 bulbs 38 are suitably arranged in proximity to the container 35 and a conductor wire 39 is led from a suitable source of current supply, indicated by the numeral 40, and is connected to one terminal of the sockets for each 110 of the electric light bulbs. A conductor wire 41 is led from the other side of the source of current supply and electrically connected with the shaft 42 of a flasher 43 which may be of the type previously described and may 115 comprise a disk 44 of insulating material carrying two series of contacts 45 and 46 upon its face electrically connected with the shaft 42. Brushes 47 and 48 are arranged in juxtaposition to the flasher disk and respectively 120 coat with the contact strips 45 and 46. A conductor wire 49 is led from the brush 47 and connected to the other terminals of the sockets for the blue light bulbs 37, and a conductor wire 50 is led from the brush 48 125 and connected to the terminals of the sockets for the red light bulbs 38. It will be evident that in the operation of the flasher 43, and when the container 35 is flooded with blue light rays, it will appear 130

substantially black or opaque, and the container 36 therein will be invisible. However, when, in operation of the flasher, the display is flooded with red light rays, the container 5 35 will apparently vanish and the container 36, which is of smaller size, will appear substantially black or opaque and, if very fine wires are employed in suspending or supporting the container 36 within the container 35, 10 these will not be visible when the container 36 is displayed and therefore the appearance will be that of the container being suspended in mid-air without any visible means of support. The principles of the invention as 15 exemplified in this form thereof may of course find embodiment in various other arrangements of various other objects within investing mediums.

In the embodiment of the invention shown 20 in Figure 1 of the drawings the container 1 and contents thereof are displayed under sources of illumination exterior thereto, but in the embodiment shown in Figure 4, in which the container is indicated by the numeral 51 and the contents by the numeral 52, the red and the blue light bulbs, indicated respectively by the numerals 53 and 54, are arranged within the container and more or less surrounded by the contents thereof, it 25 being understood that the arrangement of the bulbs will be such as to produce the best illuminating effects. In this embodiment, the container or investing medium 51 is red in color and substantially transparent as in the 30 instance of the containers heretofore described, and the invested objects or in other words the contents 52 is represented in green. The numeral 55, in this figure, indicates a conductor wire which constitutes a common 35 return to one side of a source of current supply 56, from one terminal of the sockets for all of the light bulbs. A conductor wire 57 leads from the other side of the source of current supply to the shaft 58 of a flasher 59 40 which does not differ materially from the flashers before described and includes a rotary disk 60 of insulating material bearing upon its face the contacts 61 and 62. Brushes 63 and 64 are arranged to respectively coat 45 with the contacts 61 and 62, and a conductor wire 65 is led from the brush 63 and connected with the other terminal of the socket of the blue light 54, and a conductor wire 66 is led from the brush 64 and connected with the 50 other terminal of the socket for the red light bulb 55. It will now be evident that in the 55 operation of the flasher and as the bulb 54 is lighted, the container and its contents will be illuminated with the blue light rays so 60 that the container will appear substantially opaque, and, on the other hand, when the red light bulb 53 is lighted, the investing medium constituting the container will be rendered substantially invisible, and the 65 contents 52 will be rendered visible.

Figures 5 and 6 of the drawings illustrate two appearances of an identical image as displayed under light rays of contrasting colors in accordance with the principles of the invention. This particular embodiment of the 70 invention is directed to the display of wearing apparel, and in the said figures the numeral 67 indicates a dummy such as those employed in clothing stores, or the principles of the invention might be applied to a living 75 model. The representation is that of a female and, in Figure 5, the dummy is attired in a dress 68 which is red in color or it may comprise various shades of red, and this dress is of a material which is substantially transparent to light rays and capable of being fashioned to exactly resemble a dress made of cloth material. A hat 69 may also be provided upon the dummy and made of the same 80 material as the dress 68 and be of the same color as the dress. The dummy is also attired in underclothing as for example a corset 70 which may be white in color, and stockings 71 which may be blue in color. Under 85 white light rays as for example in daylight hours, the dummy will appear substantially as shown in Figure 5 of the drawings, the dress 68, hat 69 and stockings 71 appearing in their natural colors. Under display conditions, as for example at night, the attired 90 dummy will be flooded first with green or blue-green light rays from any suitable source which source is not shown inasmuch as the previously described embodiments are sufficiently detailed to render the manner of 95 illumination clear, and the hat 69 and the dress 68 will appear black whereas the stockings 71 will appear substantially white. When the dummy is flooded with red light, 100 the dress 68 and hat 69 will completely disappear inasmuch as these articles of wearing apparel are represented in red, but the corset 70 will be displayed substantially white in color and the stockings 71 will appear substantially black due to the fact that 105 they are of a color contrasting with the color of the light rays under which the dummy is illuminated. It will be understood that the sources of illumination under which the dummy is displayed may be arranged in any suitable manner and that the dummy may be either stationary or may be supported upon 110 a turn-table so as to revolve during the periods of illumination and thereby display the articles of wearing apparel in a more thorough and effective manner.

Figures 7 and 8 of the drawings illustrate the application of the principles of the invention to the display of theatrical transformation effects and in Fig. 7 the numeral 72 indicates a bath house which may be constructed upon a stage 73 with any appropriate surrounding scenic displays 74, and this bath house is made of light ray transmitting material such for example as thin celluloid 115 120 125 130

and is of a distinctive pigment color as for example red, the house being provided with a door 75 which may be swung open and closed. The numeral 76 indicates an actress attired 5 in street costume as for example a dress 77 which is of substantially the same material as the dress 68 in the previously described embodiment of the invention, and red in color to correspond with the color of the bath 10 house. The actress is also illustrated as wearing a hat 78 which is likewise red in color and of any suitable light ray transmitting material. The actress is further attired in a bathing suit 79 as shown in Fig. 8 of the 15 drawings, and this suit is green in color or of any other color substantially contrasting with the color of the dress 77. It will now be understood that when the stage is flooded with white light rays the bath house 72 will 20 appear red in color and have a solid and substantial appearance, and the actress may, in the carrying out of the invention, advance across the stage, enter the bath house, and close the door thereof. Then if the stage be 25 flooded with red light rays, the bath house will instantly disappear as will also the dress 77 and hat 78 worn by the actress, and the actress will appear in the bathing suit 79 alone. Therefore, in this manner there may 30 be produced the effect of a female, fully attired, entering a bath house and then instantly appearing clothed in a bathing suit, the transformation being effected in a moment's time so that the change in the appearance of 35 the scenic setting of the stage is startling and mystifying. Of course the illumination of the stage may be effected by spot lights or any other arrangement of white and red light sources and the red light rays would be directed onto the bath house at the proper moment, at the discretion of an attendant whose 40 duty it is to manipulate the switches controlling the supply of current to the white and red light sources. When the stage setting is illuminated with red light rays the bathing suit 79 will of course appear substantially black. It will be understood of course that 45 after the red light rays have been projected for a sufficient period of time to effect the transformation in appearance of the actress, and while the actress is still within the bath house, the supply of current to the red light sources of illumination may be cut off and

the stage illuminated with white light rays, and while it is so illuminated, the actress may 55 open the door of the bath house and step out onto the stage, apparently having changed to her dress costume in a moment's time.

It will be understood that in the embodiment of the invention illustrated in Figures 60 7 and 8, the actress, clothed in the bathing suit 79, constitutes an invested object, and the dress 77, hat 78, and bath house 72 constitute an investment, in accordance with the principles of the invention. 65

Having thus described the invention, what I claim is:

1. The method of selectively displaying a container and its contents which comprises representing the contents in a distinctive pigment color, arranging the contents completely within a container of transparent material of a pigment color substantially complementary to the pigment color of the contents, representing upon the container, in a pigment 70 color corresponding substantially to the pigment color of the contents, matter appertaining to the contents, displaying the assemblage under light rays of a spectral color substantially corresponding to the pigment color of the contents, whereby to effect the appearance of the container as substantially black and the said matter thereon as substantially white, and at the same time effect obliteration of the contents, and then displaying the assemblage under light rays of a spectral color 75 substantially corresponding to the pigment color of the container, whereby to effect obliteration of the container and display or appearance of the contents. 80

2. Display apparatus comprising a container of transparent material of a distinctive pigment color, contents housed completely within the container and of a distinctive pigment color different from the first mentioned color, the container having represented thereon in a pigment color corresponding substantially to the pigment color of the said contents, matter appertaining to the contents, and means for successively displaying the assemblage under light rays of contrasting spectral colors, one corresponding substantially to one of the pigment colors. 95 100

In testimony whereof I affix my signature.

RICHARD M. CRAIG. [L. S.]
